WATTHOUR METER SHUNT ASSEMBLY

Frederick W. Witte, Union, N. J., assignor to Westinghouse Electric Corporation, East Pittsburgh, Pa., a corporation of Pennsylvania

Application April 12, 1954, Serial No. 422,295

5 Claims. (Cl. 324—138)

This invention relates to magnetic shunt assemblies and it has particular relation to magnetic overload shunt assemblies for watthour meters.

It is well-known in the art that magnetic overload shunts are desirable for watthour meters in order to improve the accuracy of such meters over a large range of load variations. A conventional magnetic shunt assembly for a watthour meter may include a magnetic shunt member which is positioned on a non-magnetic base carrier or spacer member. These members are secured to each other in a suitable manner such as by rivets or bent tabs. Examples of such prior art construction of magnetic shunt assemblies will be found in the R. M. Leippe Patent 2,169,029 and T. D. Barnes Patent 2,177,274.

In accordance with the invention, magnetic shunt member is embedded entirely or partly in a suitable moldable material. Although the moldable material may be of a non-metallic nature such as a phenolic resin, preferably a die-casting metallic alloy is employed as the material. A low-melting-point lead-base alloy has been found particularly desirable.

During a molding operation, the moldable material flows uniformly over the magnetic shunt member and engages the magnetic shunt member over large areas without applying local stresses or strains thereto. Since dimensions may be maintained accurately in the moldable material, the shunt member is located accurately with respect to the accompanied carrier member and the absence of local stresses and strains assures the absence of changes in physical locations as well as magnetic properties of the shunt assembly.

If desired, the magnetic shunt member may be completely embedded in the associated carrier member. However, in a preferred embodiment of the invention, the face of the shunt member is exposed. The molded carrier member preferably has a rim which completely surrounds the periphery of the shunt member and protects it at all times.

The shunt assembly is applied to a watthour meter electromagnet by wedging it between the current pole pieces of the electromagnet. The material employed for the carrier member is readily wedged between the pole pieces and engages them to retain the shunt assembly accurately in operative position. This is particularly true if the pole pieces are of laminated construction for the reason that the carrier member tends to interlock with the laminations of the pole pieces to prevent subsequent displacement of the shunt assembly.

If a moldable material is of a type which wets the surfaces of the shunt member and adheres thereto, retention of the shunt member by the carrier member is assured. In a preferred embodiment of the invention, the two members are interlocked with each other to assure permanent assembly thereof. Inasmuch as the shunt member is fully supported by the carrier member, no limitations are imposed on the shaping and material employed for the shunt member.

2

It is, therefore, an object of the invention to provide an improved magnetic shunt assembly.

It is a further object of the invention to provide a magnetic shunt assembly wherein a magnetic shunt member is molded in a carrier member.

It is another object of the invention to provide a magnetic shunt assembly wherein a die-casting alloy protects at least two edges of a magnetic shunt.

It is also an object of the invention to provide a magnetic shunt assembly wherein a shunt member is embedded in a die-casting alloy which surrounds at least the edges of the magnetic shunt member and one face of the shunt member.

It is an additional object to provide a watthour meter having spaced pole pieces and an improved shunt assembly including a molded carrier member extending between the pole pieces.

Other objects of the invention will be apparent from the following description taken in conjunction with the accompanying drawing, in which:

Figure 1 is a view in rear elevation of a watthour meter embodying the invention;

Fig. 2 is a view in top plane, with parts broken away, of a magnetic shunt assembly employed in the watthour member of Fig. 1, together with the associated pole pieces; and

Fig. 3 is a view in cross section of the shunt assembly illustrated in Fig. 2 taken along the line III—III and located in a mold cavity.

Referring to the drawing of Fig. 1, a watthour meter 1 having an electromagnet 3 and an electro-conductive armature or disc 5 which is mounted for rotation about its axis relative to the electromagnet 3 is shown.

The electromagnet 3 includes a magnetic structure constructed of soft magnetic material to provide a voltage pole piece 7 having a pole face 7P and a pair of spaced parallel current pole pieces 9 and 11 having pole faces 9P and 11P. By inspection of Fig. 1, it will be noted that the pole faces 9P and 11P are disposed in a common plane and are spaced from the pole face 7P of the voltage pole pieces to define an air gap 13 in which a portion of the disc 5 is located.

In order to establish a magnetic field in the air gap 13, a voltage winding 15 surrounds the voltage pole piece 7 and when energized directs magnetic flux through the pole piece into the air gap. Current windings 17 and 19, respectively, surround the current pole pieces 9 and 11. When the windings 17 and 19 are suitably energized a magnetomotive force is developed between the pole faces 9P and 11P for the purpose of directing magnetic flux into the air gap 13. The magnetic structure of Fig. 1 conveniently is constructed of a plurality of similar thin laminations L (Fig. 2) which are secured to each other by means of rivets 21 passing through the laminations in a direction transverse to the planes of the laminations.

Inasmuch as watthour meters are well-known in the art, a more detailed discussion of the electromagnet of Fig. 1 and its operation is unnecessary.

As shown in Fig. 1, the pole pieces 9 and 11 have lips 9L and 11L which project from the pole pieces toward each other adjacent the pole pieces 9P and 11P. Portions of the lips are undercut to define retaining ledges 9E and 11E for the purpose of retaining therebetween a shunt assembly. The shunt assembly has a protuberance 25 which projects into the space between the lips 9L and 11L.

As shown in Figs. 2 and 3, the shunt assembly 23 includes a magnetic shunt member 27 and a carrier member 29. The shunt member 27 extends between the pole pieces 9 and 11 adjacent the air gap 13. For low energizations of the windings 17 and 19, the shunt member is designed to operate in unsaturated condition and con-

sequently shunts a substantial percentage of the magnetic flux produced by these windings away from the air gap. As the energization of these windings increases, the shunt begins to saturate and as it saturates, a smaller proportion of the magnetic flux produced by the windings 17 and 19 is shunted away from the air gap. This compensates for the well-known tendency of the watthour meter to operate too slowly at larger energizations of the current windings. As well understood in the art, the term saturated is employed to refer to decremental permeability or effective decrease in permeability or relatively fast reduction in permeability, of the magnetic shunt. By proper selection of the proportions of the magnetic shunt the rotation of the disc 5 can be substantially proportional to the power measured by the watthour meter over a large range of variations of power.

As previously pointed out, the carrier member 29 preferably is constructed of a moldable material. In a preferred embodiment of the invention, the moldable material is a die-casting alloy. If the magnetic shunt member 27 is constructed of a cold-rolled steel which is properly cleaned and fluxed if necessary, the moldable material employed for the carrier member may be selected to wet the surface of the shunt member and adhere directly, thereto.

As previously pointed out, the preferred moldable material is a lead-base material containing more than 50% lead. As a specific example of such a material, the carrier member may be constructed of a die-casting alloy containing 78% to 81% lead, 14% to 16% antimony, and 4% to 6% tin, by weight. However, the constituents may vary appreciably from these proportions with good results.

The moldable material may be applied to the magnetic shunt member 27 in a suitably shaped cavity of a mold 31 having a base 31B and a cover 31C. The shunt member 27 is positioned in any suitable manner as on pins 33 which project into the cavity of the mold from the base 31B. One of these openings is provided adjacent each corner of the shunt member. When the shunt member is withdrawn from the mold four holes 35, 37, 39 and 41 are left in the carrier member. Transverse movement of the shunt member in the mold may be prevented, if necessary, in any suitable way as by providing the member with shallow recesses for receiving the pins 33.

Although the shunt member could be completely embedded in the moldable material, preferably the upper face of the shunt member is left exposed. As shown in Fig. 3, the upper face of the shunt member 27 is maintained in engagement with the adjacent wall of the mold 31.

To assure retention of the shunt member 27 by the carrier member 29, interlocking may be provided between the members. Two counter-sunk holes 43 and 45 are formed in the shunt member 27. During the molding operation these holes are filled by the moldable material which locks the shunt member 27 securely to the carrier member 29.

The mold may be shaped as desired to provide the desired shape of the magnetic shunt assembly. It will be noted that two edges of the carrier member are provided with partial bevels 47 and 49 for the purpose of engaging the ledges 9E and 11E of the current pole pieces. In order to facilitate insertion of the magnetic shunt assembly between the pole pieces, the bevels 47 and 49 may be made somewhat deeper adjacent their ends to provide somewhat thinner leading edges of the shunt assembly for insertion between the pole pieces. However, the main body of the shunt assembly is slightly longer than the distance between the ledges 9E and 11E to provide a press fit. Consequently, the shunt assembly is firmly wedged into a final position.

Because of the material employed a secure interlocking is provided between the carrier member and the

laminations of the pole pieces. Consequently, following installation of the shunt assembly, accidental displacement thereof does not occur.

The rigidity of the shunt assembly is increased by providing the projection 25 adjacent the central part of the shunt assembly. This projection also improves the flow of the moldable material which is inserted into the mold cavity through a suitable sprue 51.

The lead-base die-casting alloy has a low melting point and is introduced into the mold cavity in a very fluid condition under pressure. The material flows uniformly around the shunt member without subjecting the shunt member to local stresses. Shortly after the introduction of the moldable material, the pressure is relieved and the still fluid material in the sprue 51 drops away from the part in the restricted cross-section of the sprue which is the first to solidify. However, it will be understood that other molding or casting techniques may be employed if so desired. Following the cooling and solidification of the assembly, the cover 31C is removed from the base 31B and the shunt assembly is completely withdrawn from the mold.

It will be noted further by inspection of Figs. 2 and 3, that the carrier member provides a rim completely surrounding the periphery of the magnetic shunt member 27. Thus adequate protection is provided against bending or other injury to the magnetic shunt member. If the moldable material is of a type that adheres firmly to the shunt member, it also provides good protection against corrosion of the shunt member.

Although the invention has been described with reference to specific embodiments, therefore, numerous modifications falling within the spirit and scope of the invention are possible. Consequently, the illustrations in the drawing and the description herein presented are to be construed in an illustrative rather than a limiting sense.

I claim as my invention:

1. In a watthour meter, an electromagnet comprising a pair of spaced magnetic current pole pieces having pole faces substantially in a common plane and a magnetic voltage pole piece having a pole face spaced from the plane to define an air gap therebetween, current winding means associated with the current pole pieces for establishing, when energized, a magnetomotive force between the pole faces of the current pole pieces, and voltage winding means for directing, when energized, magnetic flux through the voltage pole piece, in combination with a shunt assembly disposed between the current pole pieces adjacent said plane for shunting magnetic flux produced by the current winding means away from said air gap, said shunt assembly comprising a magnetic shunt member extending substantially between the current pole pieces and designed to saturate within the range of said magnetomotive force for which the electromagnet is designed, and a carrier member wedged between the current pole pieces, said carrier member having a cavity proportioned to receive snugly the shunt member, said carrier member and the shunt member having uniform surface engagement throughout substantial engaging surfaces, said carrier member comprising a die-casting alloy molded in intimate engagement with the shunt member, said carrier member engaging said current pole pieces to space the shunt member from the pole pieces.
2. In a watthour meter, an electromagnet comprising a pair of spaced laminated magnetic current pole pieces having pole faces substantially in a common plane and a magnetic voltage pole piece having a pole face spaced from the plane to define an air gap therebetween, current winding means associated with the current pole pieces for establishing, when energized, a magnetomotive force between the pole faces of the current pole pieces, and voltage winding means for directing, when energized, magnetic flux through the voltage pole piece, in combination with a shunt assembly disposed between the cur-

rent pole pieces for shunting magnetic flux produced by the current winding means away from said air gap, said shunt assembly comprising a magnetic shunt member extending substantially between the current pole pieces and designed to saturate within the range of said magnetomotive force for which the electromagnet is designed, and a carrier member wedged between the current pole pieces, said carrier member comprising a uniform die-casting material embedding and intimately engaging a substantial portion of the shunt member and engaging the edges of the laminations of the current pole pieces.

3. In a watthour meter, an electromagnet comprising a pair of spaced magnetic current pole pieces having pole faces substantially in a common plane and a magnetic voltage pole piece having a pole face spaced from the plane to define an air gap therebetween, current winding means associated with the current pole pieces for establishing, when energized, a magnetomotive force between the pole faces of the current pole pieces, and voltage winding means for directing, when energized, magnetic flux through the voltage pole piece, in combination with a shunt assembly disposed between the current pole pieces for shunting magnetic flux produced by the current winding means away from said air gap, said shunt assembly comprising a magnetic shunt member extending substantially between the current pole pieces and designed to saturate within the range of said magnetomotive force for which the electromagnet is designed, and a carrier member held by engagement with the current pole pieces, said carrier member comprising a uniform die-casting metal alloy molded around one face and the sides of the shunt member to provide a rim surrounding the shunt member.

4. In a watthour meter, an electromagnet comprising a pair of spaced magnetic current pole pieces having pole faces substantially in a common plane and each having a lip adjacent said plane, said lips projecting in directions towards each other, the free ends of the lips being spaced from each other, said pole pieces comprising laminations each transverse to the plane and parallel to said directions, and a magnetic voltage pole piece having a pole face spaced from the plane to define an air gap

therebetween, current winding means associated with the current pole pieces for establishing, when energized, a magnetomotive force between the pole faces of the current pole pieces, and voltage winding means for directing, when energized, magnetic flux through the voltage pole piece, in combination with a shunt assembly disposed between the current pole pieces for shunting magnetic flux produced by the current winding means away from said air gap, said shunt assembly comprising a magnetic shunt member extending substantially between the current pole pieces adjacent the pole faces thereof and designed to saturate within the range of said magnetomotive force for which the electromagnet is designed, and a carrier member wedged between the current pole pieces, said carrier member engaging said lips and having a portion extending between the lips, said carrier member comprising a die-casting material embedding a substantial portion of the shunt member, said shunt member having an exposed face defining a portion of said air gap.

5. An electromagnet comprising a magnetic structure having pole pieces, said pole pieces having pole faces defining an air gap, winding means effective when energized for establishing a magnetomotive force between said pole faces to produce a magnetic field in the air gap, and a magnetic shunt assembly disposed to shunt magnetic flux produced by said magnetomotive force away from the air gap, said magnetic shunt assembly comprising a magnetic shunt member positioned to carry magnetic flux produced by the magnetomotive force and proportioned to saturate within the range of energization of the winding means, and a carrier member substantially embedding the shunt member, said carrier member comprising a die-casting metal alloy molded about said shunt member and abutting said pole pieces, said carrier member spacing said shunt member from the pole pieces.
